EYELID CAP

William G. Bauer, New York, N. Y.

Application December 7, 1935, Serial No. 53,300

2 Claims. (Cl. 2—15)

This invention relates to a protective eye lid cap for the protection of the eyes of patients or persons undergoing treatment beneath sun-lamps in solariums or the like against the pernicious influence of the infra-red rays during massage or similar treatments, or during taking a sunbath at the shore or other localities, and it is the principal object of my invention to provide a comparatively simple and inexpensive article which nevertheless is durable and highly efficient in operation.

Another object of my invention is the provision of an eye lid cap equipped with an exchangeable sanitary lining of suitable material. Still another object of my invention is the provision of an eye lid cover and cap adapted to the shape of the eye lid and provided with a suitable handle or handles allowing the convenient handling of the cap and so shaped as to serve as holder for the lining.

A further object of my invention is the provision of an eye lid cap the handles of which are spaced from the body thereof to provide a means for threading or otherwise securing thereto a cord, elastic band or the like by means of which the cap may be conveniently attached to the wrist of a bather for instance if used on the strand or sea shore.

A still further object of my invention is the provision of an eye lid cap or cover preferably made from suitable material as for instance cellulose acetate or other moldable plastic material and suitably colored.

These and other objects and advantages of my invention will become more fully known as the description thereof proceeds, and will then be specifically defined in the appended claims.

In the accompanying drawing forming a material part of this disclosure:

Fig. 1 is a top plan view of an eye lid cap constructed according to my invention.

Fig. 2 is a longitudinal section through the cap on line 2—2 of Figure 1.

Fig. 3 is a cross-section on line 3—3 of Figure 1.

Fig. 4 is a bottom plan view of the cap with the lining partly broken away.

Fig. 5 is a perspective view of a modified form of my cap with a fastening means threaded through its handles.

Fig. 6 is a top plan view of another modification of the cap.

Fig. 7 is a longitudinal section through the cap, on line 7—7 of Figure 6.

Fig. 8 is a cross-section on line 8—8 of Figure 6.

As illustrated in Figures 1 to 4, the preferred form of my invention shows an eye lid cap or cover comprising a body 10 preferably curved to fit the curvature of the eye lid and molded from any suitable plastic material or cut from a block of suitable material, and equipped with a radially disposed handle or grip 11 one or both ends of which are re-entrantly bent, as at 12, to loosely engage the lower face of the body so as to hold exchangeably a sanitary lining 13.

In the form of my invention illustrated in Figure 5, the suitably curved body part 14 of the cap has two radially arranged handles or grips 15, 16 formed therewith or attached thereto and provided with openings through which a cord, elastic band or other appropriate fastening means are drawn or passed by means of which the cap may be conveniently attached to the 20 wrist of a bather if used on the strand.

In the form of my invention illustrated in Figures 6, 7 the suitably curved body part 18 of the cap has formed therewith, preferably near its ends the handles or grips 19, 20 having openings 21, 22 or spaces through which a suitable fastening means 23 is threaded or passed by means of which the cap may be secured to the wrist or the like of a bather or user. Intermediate its ends the cap body has formed therewith two oppositely disposed holder members 24, 25 with their inner ends spaced from one another, as at 26, while their outer ends are re-entrantly bent to loosely engage the lower face of the cap and serve as holders for the sanitary lining 27.

The operation and use of my protective eye lid caps will be entirely clear from the above description by having simultaneous reference to the drawing, and it will be clear that by the use of the cap the eye will be efficiently protected against the sun rays or the rays of sun-lamps or the like while the exchangeable sanitary lining will safeguard the person undergoing treatment against contagion, and if necessary a wad of cotton or other hygienic material may be interposed between eye lid and cap. The elastic fastening means will provide a means to securely and conveniently carry the cap on the person against loss and misplacement on the beach or the like, while the material of the cap may have any color to suit any taste, and may be so selected as to allow a manufacture of the cap at reasonable cost.

It will be understood that I have disclosed as

examples a few of the many possible forms for practically making my cap, and that I may make such changes in its general arrangement and in the construction of its minor details as come 5 within the scope of the appended claims without departure from the spirit of my invention and the principles involved.

Having thus described my invention, what I 10 claim as new and desire to secure by Letters Patent is:

1. An eye lid cap comprising a body, a lining for said body, a handle, and means associated with said handle to exchangeably hold said lining to said body.

2. An eye lid cap or cover comprising a curved 5 body, a sanitary lining therefor, and a radial handle or grip thereon having its end formed as a holder for the sanitary lining to allow an exchange of the same.

WILLIAM G. BAUER. 10
